DESIGN FOR A BOTTLE VENDING MACHINE CASE

Ernest Frederick Thomson, Tuckahoe, N. Y., as
signor to C. Earl Hovey, Kansas City, Mo.,
trustee

Application February 11, 1946, Serial No. 126,482

Term of patent 14 years

(Cl. D52—3)

To all whom it may concern:

Be it known that I, Ernest Frederick Thomson, a citizen of the Dominion of Canada, residing at Tuckahoe, in the county of Westchester and State of New York, have invented a new, original, and ornamental Design for a Bottle Vending Machine Case, of which the following is a specification, reference being had to the accompanying drawing, forming a part thereof.

Fig. 1 is a perspective view of a bottle vending machine case, showing my new design; and

Fig. 2 is a side elevational view thereof.

I claim:

The ornamental design for a bottle vending machine case, as shown.

ERNEST FREDERICK THOMSON.
